UNITED STATES PATENT OFFICE.

GUY DINCOGNITO, OF CHICAGO, ILLINOIS.

COLLAPSIBLE CANNING RACK.

1,404,348.

Specification of Letters Patent. Patented Jan. 24, 1922.

Application filed March 13, 1920. Serial No. 365,582.

To all whom it may concern:

Be it known that I, GUY DINCOGNITO, a citizen of the United States, and a resident of the city of Chicago, county of Cook, and 5 State of Illinois, have invented certain new and useful Improvements in Collapsible Canning Racks, of which the following is a specification.

My invention relates to improvements in 10 collapsible canning racks, and has for its object the provision of an improved construction of this character which is simple and efficient in use, and capable of economical manufacture.

15 Other objects will appear hereinafter.

The invention consists in the combinations and arrangements of parts hereinafter described and claimed.

The invention will be best understood by 20 reference to the accompanying drawings forming a part of this specification, and in which,

Fig. 1, is a longitudinal section of a collapsible canning rack embodying the invention,

Fig. 2, a top plan view of the same,

Fig. 3, a perspective view of one of a plurality of supporting bars employed in the construction, and

30 Fig. 4, an end view, on a small scale, of the rack.

The preferred form of construction, as illustrated in the drawings, comprises a lower open work wire frame 5 and an upper 35 open work wire frame 6 adapted to be arranged one above the other, as shown, the cross bars of said frames being staggered or out of registration with each other, as indicated. The frames 5 and 6 are connected 40 together at their opposite sides by means of supporting bars 7 in the form of comparatively wide metallic strips or bars having eyes or loops formed therein and having comparatively tight frictional engagement

45 with the side bars of the frames, as indicated. The bars 7 are extended at their lower ends somewhat beyond the frame 5 to form supporting legs 10 adapted to support said frame 5 well above the bottom of a 50 boiler or the like. Suitable lifting handles 11, in the form of wire loops, are pivotally connected with the end bars of the frame 6, as shown, to facilitate handling of the rack.

In use, the frame is distended as indicated, 55 with the frame 6 positioned above the frame

5, the openings in the frame 6 coming directly above the cross bars in the frame 5, whereby cans or jars, for preserving fruits, vegetables, or the like, may be inserted through the openings in the frame 6 and will 60 rest upon the cross bars of the frame 5. The rack is then employed in the usual way to facilitate cooking of the material in the cans or jars, and when this is completed the handles 11 facilitate removal thereof from 65 the boiler. In collapsing, all that is necessary is to swing the upper frame laterally to one side, as indicated by the dotted lines in Fig. 4, whereupon the frame 6 may be brought down to a plane just above that of 70 the frame 5, and the handles 11 folded inwardly. By providing supporting bars or legs 7 in the form of comparatively wide flat strips bent to engage the side bars of the frames with a tight frictional fit, the frame 75 is held in distended position with sufficient rigidity to support and position the cans or jars. The breadth of the bars 7 also has sufficient longitudinal stiffening effect on the rack to obviate any necessity for longitudinal bracing. The rack thus provided is especially adapted for use in canning or preserving fruits and vegetables, although capable of use for other purposes. The specific 80 form and arrangement of parts is a simple 85 and effective one for the purpose.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the 95 appended claims.

Having described my invention, what I claim as new and desire to secure by Letters Patent is:—

1. A collapsible rack of the class described 100 comprising upper and lower frames; and connecting bars extending between opposite sides of said frames, said bars being in the form of strips bent to form loops frictionally engaging the sides of said frames, 105 said bars being extended beyond said lower frame to constitute supporting legs, substantially as described.

2. A collapsible rack of the class described comprising upper and lower frames; con- 110

necting bars extending between opposite sides of said frames, said bars being in the form of strips bent to form loops frictionally engaging the sides of said frames; and 5 handles pivotally connected with the ends of said upper frame, substantially as described.

3. A collapsible rack of the class described comprising upper and lower frames; connecting bars extending between opposite sides of said frame, said bars being in the form of strips bent to form loops frictionally engaging the sides of said frames, said bars being extended beyond said lower frame to constitute supporting legs; and handles 10 pivotally connected with the ends of said upper frame, substantially as described.

4. A collapsible canning rack comprising upper and lower frames, said frames con-

sisting of open wire work; connecting bars extending between opposite sides of said frames, said bars being in form comparatively wide strips bent to form loops frictionally engaging the sides of said frames, said bars being extended beyond said lower frame to constitute supporting legs; and 20 handles for said rack, said handles consisting of wire loops pivotally connected with the opposite ends of said upper frame, substantially as described.

In testimony whereof I have signed my 30 name to this specification in the presence of two subscribing witnesses.

GUY DINCOPNITO.
